FIG. 4.

Inventor:

HEYMAN ROSENBERG

By Edgar M. Kitchin,

his attorney.

UNITED STATES PATENT OFFICE

2,015,158

BOTTLE TAP

Heyman Rosenberg, New York, N. Y.

Application July 21, 1932, Serial No. 623,887

1 Claim. (Cl. 225—22)

This invention relates to improvements in apparatus for facilitating the discharge of liquid from bottles, and more particularly the delivery of carbonated beverages from bottles having the conventional crimped-on form of caps.

Among the objects in view is the production of a valve structure adapted for direct application through a bottle cap without removal of the cap, the parts having maximum simplicity and minimum cost of production.

A further object in view is the simple, inexpensive, and effective anchorage of the penetrating tube in the material of the conventional bottle cap in a manner to insure a pressure-tight joint therewith, and a still further object is the provision of means for accomplishing this result repeatedly with the same inexpensive instrumentalities.

With these and further objects in view as will in part hereinafter be stated and in part become apparent, the invention comprises certain novel constructions, combinations, and arrangements of parts as subsequently specified and claimed.

In the accompanying drawing,—

Figure 1 is a view in side elevation of an embodiment of the present invention illustrated as applied to a bottle cap, a fragment of the bottle neck being shown.

Figure 2 is a similar view of the same taken from a plane at right angles to the plane of observation for Figure 1.

Figure 3 is a top plan view thereof.

Figure 4 is an enlarged, longitudinal section therethrough, parts being seen in elevation.

It has heretofore been proposed to deliver carbonated beverages from bottles by taps or valves or like siphoning devices applied by penetration of the crimped cap so that only such quantities need be delivered at any one time from the bottle as required and the balance preserved under the bottled pressure for future use; but such previously proposed devices have been of somewhat involved and expensive construction and lacking in dependability for repeated use, and also lacking in capacity for invariably effecting a pressure-tight seal with the bottle cap. The present invention overcomes these difficulties by providing an apparatus of so simple construction as to be of minimum cost, and, in fact, so inexpensive in production as to be available for one-time use when required without material loss, and at the same time the device is adapted for many times repeated use with an invariably resulting pressure-tight connection with the bottle cap. Also, the size of the organized structure is

materially reduced over that of previously known attempts, so that but a minimum space is occupied for packing, shipment, and handling and for accommodation where the bottle is to be inserted in a reduced space, as in a refrigerator, with the improved valve applied to the bottle cap.

Referring to the drawing by numerals, 1 indicates an ordinary carbonated beverage bottle having the usual flange terminus 2 of the bottle neck which is engaged and gripped by the crimps 10 of the conventional crimped-on cap 4. Cap 4 is customarily formed of metal with an inner liner 5 of cork or other appropriate sealing material. These parts are all common and well known in the handling of carbonated beverages.

The invention itself relates to the means for penetrating the cap 4 to enable controlled withdrawal of the carbonated beverage from within the bottle 1, which means comprises a tubular screw 6, a tap sleeve 7 to which the screw 6 is fixed, a valve 8 for controlling discharge from the sleeve 7, an operating thumb button 9 for removing the valve 8 from its seat, an appropriate seat 10 for the valve 8, and a pressure-retaining gasket 11 surrounding the valve stem 12 which connects valve 8 with thumb button 9. The sleeve 7 is preferably provided with a reduced bore portion 27 for a medial part of the sleeve, and then with enlarged terminal portions 13 and 14 leaving annular shoulders 15 and 16. The gasket 11 is arranged within the enlarged portion 13 and seated against the shoulder 15 and proportioned to snugly engage the valve stem 12, allowing the stem to slide longitudinally therethrough, and the valve seat 10 is arranged in the enlarged portion 14 and rests snugly against the shoulder 16.

The valve seat 10 and gasket 11 may be formed of appropriately vulcanized rubber, or other available material, adapted to be readily rendered snug-fitting against the valve and valve stem 40 respectively for preventing leakage of pressure or liquid. The valve 8 is normally maintained snugly on its seat by appropriate cushioning means stressing the valve toward its seat, and one form of such cushioning means may consist of a coiled 45 spring 17 surrounding the stem and engaging the inner face of the button 9, and at its opposite end engaging an appropriate plate or washer 18 resting against the outer face of the gasket 11 and surrounding the valve stem 12. Spring 17 is 50 tensioned to appropriately stress the button 9 outward.

The button 9 may be formed on or fixed to the valve stem 12 in any of various appropriate ways, but for ease of assemblage, inexpensiveness of 55

production, and absolute assurance of permanence of mounting, I preferably employ a device corresponding to the conventional sleeve rivet whose head constitutes the button 9 and whose sleeve is anchored to the stem 12 by being driven onto the threads of a drive pin section 19 formed on and preferably integral with the valve stem 12. The drive pin section 19 preferably corresponds in construction, material, form, and function with the drive pin set forth in my U. S. Patent No. 1,482,151, dated January 29, 1924. In other words, the section 19 is made up of high-pitched thread portions outstanding from the body of the stem 12 and hardened sufficiently for entering metal, such as soft iron or soft steel, substantially without injury to the threads, and the diameter of the section 19 is proportioned to the diameter of the bore of the sleeve rivet, as clearly seen in Figure 4, to cause material of the sleeve to be entered by the threads and to flow down into the valleys between the threads after the manner described in my above-mentioned patent when the sleeve is driven home over the drive pin section 19, and thus an effective interlock is produced between the button 9 and the valve stem 12. Of course, the valve stem must be properly located in the sleeve 7 with the valve seat 10, gasket 11, plate 18, and spring 17 in place before the sleeve is forced down along the drive pin section 19.

The screw 6 is generally of the construction, material, form, and function of the screw set forth in my U. S. Patent No. 1,411,184, dated March 28, 1922, except that the penetrating or tapered end portion of screw 6 does not require the presence of the thread, though such presence would not be harmful. Thus, the threads of the screw 6 are hardened sufficiently for entering metal, such as soft iron or soft steel, substantially without injury to the threads; but before the hardening operation the screw will have been provided with a passageway or port 20 preferably extending substantially axially within the screw and having a lateral portion 21 opening at the side of the screw at or adjacent the beginning of the tapering end portion of the screw. The sleeve 7 is provided with a lateral opening 22 communicating with the reduced bore 21 and proportioned to receive a drive pin section 23 at the upper end portion of the screw 6. A circumferential flange 24 preferably surrounds the body of the screw 6 at the place of juncture between the drive pin section 23 and the balance of the screw. The drive pin section 23 is substantially identical in every respect with the drive pin section 19 above described, except that section 23 may be somewhat shorter and is proportioned with reference to the lateral port 22 to be driven into engagement with the sleeve 7, as by hammer blows delivered to the flange 14, whereby the screw 6 is effectively anchored with a pressure-tight anchorage to the sleeve 7. Not only so, but the anchorage of the drive pin section 23 in the sleeve incident to the flowing of the material of the sleeve 7 into the valleys between the ribs or threads of the drive pin section 23 is so effective that the sleeve 7 may be used as a sort of handle with which the screw 6 may be revolved to insert it or to withdraw it

without any danger or likelihood of releasing or loosening of the section 23 in its engagement with the material of the sleeve 7. The degree of permanence of such an anchorage is very great, as will be apparent from the statements setting forth more in detail the facts relating thereto as found in my U. S. Patent No. 1,482,151, dated January 29, 1924.

When the valve and its parts have been properly located in the sleeve 7 and the screw 6 has been anchored thereto as described, the apparatus is complete and ready for operation, but as a means of substantial margin of safety against possible leakage a rubber or other appropriate gasket 25 may be mounted to surround the flange 15 24, and the gasket is preferable circular to afford a substantial bearing on the upper face of the cap 4 when the parts are applied to a bottle. The sleeve 7 is provided with flanged parts 26 of substantially disc form overlying the gasket 25 so as to press the gasket bodily toward the bottle cap when the parts are assembled in operative relation to a bottle.

In applying the valve or tap, the operator merely inserts the penetrating point of screw 6 25 through the cap 4 and then revolves the instrument causing the threads of screw 6 to enter the metal of cap 4 and find anchorage thereto after the manner set forth in my above-mentioned Patent No. 1,411,184, and also after the manner set forth in my U. S. Patent No. 1,299,232, dated April 1, 1919. The thread of screw 6 also finds intimate contact with the cork 5, but the chief anchorage is to the metal 4, and the joint is sufficiently tight to be non-leaking under all normal 35 conditions. As a means of additional safety, the gasket 25 will preferably be employed and the engagement of the thread of the screw 6 with the bottle cap is sufficiently strong to enable the sleeve 7 and its flange 26 to press the gasket 25 tightly 40 against the bottle cap.

While, of course, the parts may be made of any appropriate material, the sleeve 7 is preferably a die casting without machining. No machining is required in view of the character of the valve seat 45 and gasket and the arrangement of parts provided. All of the parts except the spring, the gasket and valve seat and the screw 6 may be made of aluminum, or other appropriate material. The screw 6 is preferably of iron or steel so as to 50 enable the requisite hardened condition.

What is claimed is:

In bottle tapping valves, the combination of a sleeve having a reduced intermediate portion of its bore and enlarged terminal portions of its 55 bore providing shoulders at the ends of the intermediate portion, a valve seat engaging one of said shoulders, a sealing gasket engaging the other shoulder, a valve movably engaging the valve seat, a valve stem carrying the valve and extending through and in pressure-tight engagement with the gasket, a thumb button at the free end of the valve stem, a spring between the thumb button and the gasket surrounding the valve stem, and bottle cap penetrating means extending from the sleeve and having a port leading to the said reduced portion of the bore of the sleeve.

HEYMAN ROSENBERG.
